Company, Boston, Mass., a corporation of Dela-
ware

Original application May 19, 1933, Serial No.
671,870. Divided and this application March
13, 1934, Serial No. 715,349. Renewed Septem-
ber 19, 1938.

15 Claims. (Cl. 177—386)

1

The present application is a division of my co-
pending application filed May 19, 1933, Serial
No. 671,870, Patent Number 2,380,931.

The present invention relates to apparatus for
producing compressional waves and is applica-
ble for the production of such waves in air, wa-
ter or in other media.

In the present invention the compressional
waves produced are more particularly in the
range of so-called supersonic frequencies, that is,
frequencies which are beyond the audibility of
the human ear, although to some extent the pres-
ent invention is also applicable to the production
of high-frequency compressional or sound waves
which are situated in the upper part of the audi-
bility range of the human ear and just beyond it.

Due to the fact that metals possess great elas-
ticity and that the wave lengths of high fre-
quency compressional waves are very short in
metals, it is difficult to assume that the masses
involved in compressional-wave apparatus of
this type move as masses alone without partak-
ing in the vibration of the vibrating elements.

In the prior art devices have been used in
which a radiating surface or area was very large
as compared with the wave length of the sound to
be propagated in the propagating medium and
the radiating surface was vibrated at a plurality
of points in order to produce a plane wave or a
directed beam of sound or compressional waves.
Such devices have been usefully employed both in
so-called piezo-electric oscillators and in oscil-
lators of the magnetic type.

In supersonic oscillators of the piezo-electric
type a mosaic of piezo-electric crystals are
mounted between steel plates. The thickness of
the plates together with that of the crystals are
such as to establish a tuning in a direction per-
pendicular to the plate surface and each crystal,
in fact, vibrates that part of the plate where it is
attached. An examination of this type of oscil-
lator indicates that the whole plate does not
move with the same amplitude and that between
the places where the crystals are applied the vi-
brational energy is sometimes quite small.

In other types of oscillators the same charac-
teristics are found and while it is possible to pro-
duce some vibration over an entire plate, it has
been found a fact that the vibration is more par-
ticularly produced opposite the places where the
vibrational energy is applied. This gives evi-
dence of the fact that in high frequencies there
is difficulty in making a plate act as a diaphragm
and the tendency is for it simply to act as a
transmitting medium.

2

In devices employing other than piezo-electric
means, for instance, in oscillators of the mag-
netostrictive type, it is possible to use resonant
tubes or rods for driving a sound diaphragm over
its surface in the same phase. The difficulty,
however, of making the whole diaphragm or plate
to which the rods are attached vibrate is also
present here, and it is usually observed that the
vibration occurs more particularly at the points
where the rods or tubes, producing the compres-
sional wave energy, are attached.

I have also observed that it is quite impossible
to predict just how such plates or diaphragms
will vibrate and just what load either radiating
15 or mass load should be considered as belonging
to each operating unit. In fact, it appears that
rods or tubes similarly attached which before-
hand had the same resonant frequencies may
well after attaching have other resonant fre-
quencies. This fact alone makes it difficult to ob-
tain a uniform resonance of all the operating
units and seriously handicaps and limits the
available power output, since some units are op-
erating on resonance while other units are off
25 the resonant point. This condition also distorts
the sound beam since it is apt to destroy the uni-
form phase vibration of the entire vibrating sur-
face.

In the present system which I have devised I
30 have avoided many of these difficulties by con-
structing each unit as an independently operat-
ing unit and establishing the same resonance
point for each so that they can all operate with
the same amplitude in the same phase at the
35 same frequency. In order to produce a fixed
beam of compressional waves it is only necessary
in the present system to have a sufficiently large
number of independently operating units posi-
tioned or nested close together vibrating in the
40 same phase in order to produce a plane wave
whose width in the propagating medium will be
many times the wave length of the sound or com-
pressional wave produced.

When it is desired to produce a directive beam
45 of sound or compressional waves whose direction
can be controlled or varied, this may be done by
vibrating lines or groups of individually operat-
ing units with proper phase differences, it being
preferable under such conditions to have the in-
50 dividually operating units relatively point sources
so that each point in the medium may have the
right vibrational phase.

Figure 1 shows a fragmentary section through
the oscillator showing the rows of oscillating ele-
55 ments; Figure 2 shows a sectional view of the

modification shown in Figure 1 taken on the line 2-2 of Figure 1; Figure 3 shows a perspective of a detail of the same modification; Figure 4 shows a further modification on the same type of view as indicated in Figure 2; Figure 5 shows a section along the line 5-5 of Figure 4; and Figure 6 shows a fragmentary perspective of a detail of the same modification.

In the present application which is a division of the applicant's copending case, as stated above, the structure more particularly described and claimed is one in which a group of long flat plates make up the radiating unit. These may be assembled together very closely with the center lines of the units substantially a half wave length apart or even less or they may be made somewhat wider in construction, depending upon the particular method in which it is desired to operate the units. Where the units are wider than a half wave length, each individual unit tends to become directive and therefore such a construction should not be used unless it is desired to transmit a beam in a direction normal to the surface of the radiating units. Regardless of which type may be employed, the principles set forth in the present construction apply to the operation of the elements as long flat plates operated by strips that are resonant with the plates longitudinally in the direction of the width of the strips.

The invention is illustrated in Figures 1, 2 and 3. In Fig. 1 the magnetostrictive element comprises an elongated strip 70 which has a radiating unit 71 made integral with the end thereof. The radiating unit 71 is elongated, as indicated in Fig. 3, and may be constructed with inclined shoulders 72. The magnetostrictive strip 70 may be provided with slots 73 as indicated by the dotted lines in Fig. 2. The lower end of the strip 70 is held between similar magnetizable plates 74 and 75 made up of C-shaped laminations and thus when assembled are recessed to contain the coil 76 which, as indicated in Fig. 3, is elongated and surrounds the strip 70. At the lower end of the plate there is provided a plurality of flat head screws 77 which pass from one plate into the opposite plate and thereby clamp rigidly the end of the magnetostrictive strip 70. This furnishes a clamping mass for the magnetostrictive strip 70 which vibrates in its vertical dimension as shown in Fig. 1, and has a resonance of vibration normal to the effective radiating plane of the unit 71.

The plates 74 and 75 have upper projecting poles 78 shaped to conform to the inclined surface 73 underneath the top of the radiating element 71. In this manner the complete magnetic path for the coil 76 is through the strip 70 about the surrounding plates 74 and 75 and returning through the small air gap at the sides and underneath of the radiating plate 71.

The units indicated in Fig. 1 are in themselves independent and may preferably be made of considerable length many times the wave length of the compressional wave which it is desired to generate in the sound-propagating medium. Each of these units may be arranged to form parallel successive rows and a great number of the units may be used so that the horizontal dimension of the device may be many times the wave length of the sound produced in the propagating medium. In such an arrangement each unit will be vertically disposed and if they are independently excited by desired phase differences depending upon the distance of the units

from each other and the wave length of the sound to be generated, a beam effect will be obtained. In the modification shown in Fig. 1 the units themselves may be mounted in a large base plate 90 to which they are held by means of the screws 91. The units may individually be made watertight by providing the plates 74 and 75 and also the radiating end 71 with a proper groove 92 in which the gasket 93 might be placed to prevent water from entering into and around the coil. This watertight gasket can also serve to center and space the radiating unit 71 so that no sideways motion will be present. A row of screws 94 is provided at the end of each unit so that the units may be firmly clamped both at the top and along the sides. In the unit shown in Figs. 1, 2 and 3 a solid structure is illustrated.

In Figs. 4, 5 and 6 part of the structure is laminated. In this modification the end-radiating element 100 and the strip 101 may be built up of a series of laminations which are held tight at the top by a bolt 105 passing completely through the whole group of laminations or this element in itself may be of a solid structure. The lower end of the strip 101 is clamped between clamping plates 102 and 103 which are firmly screwed together by means of the screws 104.

The coil 106 corresponding to the coil 76 of Fig. 1 is encased by a cover built up of laminations 107 which are held together by means of the stay rods 108, 108, etc. The laminations 107 are built up in groups between which are the supporting members 109, 109, etc., through which the rods 108 also pass making a substantially rigid structure and uniting the laminations together in plates equivalent to the side plates 74 and 75 of Fig. 1. The members 109 extend downward below the laminations and rest in corners in the clamping blocks 102 and 103 to which they are held by means of the screws 110. The end radiating element 100 may be covered by means of a rubber cover 111 which may be cemented to it and also cemented to the casing 113 at the shoulder 114. As will be seen in Fig. 4, the oscillator is built up of a number of parallel units in which the radiating elements run substantially parallel.

It should be noted that in this modification as well as in the structure shown in Figs. 1, 2 and 3 that the individual units are long as compared with the wave length of the wave transmitted in the propagating medium, and the length of the unit itself may be of a different order of magnitude than the wave length of the transmitting wave.

It should also be noted that the effective radiating length of the whole oscillator may also be many times the wave length of the wave transmitted, in which case a considerable number of individual units will go to make up the entire oscillator.

In Fig. 6 is shown a perspective view of the modifications shown in Figs. 4 and 5. In this view the structure at the end of the oscillator is more clearly indicated. It will be noted that the corner which fits at the end of the last laminated group is composed of two pieces 115 and 116 which are themselves unjoined, being held to the laminated structure by means of the stay rods 108 as explained above.

Having now described my invention, I claim:

1. Means for producing a beam of compressional waves comprising a plurality of parallel elongated plates having magnetostrictive strips attached to the same, means including said magnetostrictive strips for vibrating said plates at the

desired frequency, means clamping said strips at the ends opposite the plates, said strips being tuned to resonance for the desired frequency of vibrations transverse to the long dimension of the strip.

2. Means for producing a beam of compressional waves comprising a plurality of parallel elongated radiators having magnetostrictive strips attached to the same, means including an energizing coil and said magnetostrictive strips for vibrating said plates at the desired frequency, a plurality of elongated plates positioned parallel to said strips and having projecting elements at the ends thereof, said plates being composed of magnetic material and serving as the return magnetic path for the flux passing through the magnetostrictive strips to provide clamping surface at the lower ends of said strips, each of said strips being tuned to resonance for said desired vibrations normal to said radiators.

3. Means for producing a beam of compressional waves comprising a plurality of parallel elongated radiators having magnetostrictive strips attached to and vibrating the same, an elongated coil surrounding each of said strips, a plurality of elongated plates of magnetic material positioned parallel to said strips and having portions projecting therefrom near the ends towards said strips, said projecting portions serving to provide clamping surfaces and said plates serving as the return magnetic path, means cooperating with said plates for clamping the lower ends of said strips thereto, each strip being tuned to resonance for vibrations normal to the radiators and each coil adapted to be independently connected to a separate supply source.

4. Means for producing a beam of compressional waves comprising a plurality of parallel elongated magnetostrictive strips having radiating means on a corresponding long edge of each, and being tuned to resonance for vibration normal to the radiating means, elongated coils each surrounding one of said strips, a plurality of elongated plates of magnetic material having portions projecting at the ends thereof and completing a return magnetic path for said coils enclosed by the plates and said projecting portions, means clamping the strips between plates at one set of projecting portions and means holding said plates together in parallel relation.

5. Means for producing a beam of compressional waves comprising a plurality of parallel magnetostrictive strips elongated in one dimension and resonant to the frequency desired to be produced in the width dimension, said strips having radiating means fixed on a corresponding edge of each, and being tuned to resonance for vibrations normal to the radiating means, an elongated coil surrounding each of said strips, a plurality of elongated plates of magnetic material having a recessed portion shaped to conform on one side to the contour of said coil and furnishing a return magnetic path for the flux generated by said coil and passing through said strips, means including said plates for clamping the strips between said plates at the ends thereof and means holding together said plates in parallel relation.

6. Means for producing a beam of compressional waves comprising a plurality of wave radiators associated together in a unitary device, each radiator having a vibrating unit having a T-shaped section, a coil surrounding the stem thereof, means of magnetic material clamping the lower end of the stem of the T, means of mag-

netic material including said clamping means for completing the magnetic circuit from the end of the stem to the cross piece of the T, and a soft rubber diaphragm covering the radiating surface of the unitary device.

7. Means for producing a beam of compressional waves comprising a plurality of wave radiators associated together in a unitary device, each radiator having a vibrating unit having a T-shaped section, a coil surrounding the stem thereof, means clamping the lower end of the stem of the T, said means including means of magnetic material external of the coil for completing the magnetic circuit to the top cross piece of the T and means between the ends of the cross piece of the T and the magnetic means to complete the closure of the coil and position the T-shaped piece.

8. Means for producing a beam of compressional waves comprising a plurality of parallel elongated plates, said plates being arranged side by side with their surfaces forming a continued plane surface, strips of magnetostrictive material attached to and supporting said plates, electromagnetic means surrounding each of said strips for energizing the same, each of said plates being free to vibrate as a single piston element.

9. Means for producing compressional waves of high frequency comprising a rectangular elongated plate, a strip of magnetostrictive material supporting said plate substantially along the middle of the same, an elongated coil positioned about said strip, a plurality of side elements of magnetic material, said elements being provided with extending flanges extending over the top and bottom of said coil and furnishing at the bottom end a clamping surface for the bottom of said magnetostrictive strip and means clamping said plates and strips together at the bottom end thereof.

10. Means for producing compressional waves of high frequency comprising a rectangular elongated radiator, magnetostrictive means for driving said radiator, means forming an enclosed casing about said magnetostrictive means, said means providing a surface extending in the same plane as said radiator and means carried between said radiator and said casing for producing a watertight joint between the same.

11. Means for producing compressional waves of high frequency comprising an elongated rectangular radiator having one side flat and the opposite side tapered to form a V-shaped section, means forming a groove at the side of said radiator, means for driving said radiator simultaneously over its whole length, magnetic means forming a casing about said driving means, said means being provided with a groove opposite said groove in said radiator and means extending between said grooves for providing a water-tight joint within said casing.

12. In a means for producing a beam of compressional waves, a radiating element having a T-shaped section formed of a plurality of T-shaped laminated strips having means binding said strips into said T-shaped section, coil means for impressing magnetic flux through the stem of said T-shaped element, a plurality of substantially C-shaped laminations of magnetic material encasing said coil means and positioned to form pole elements for a magnetic circuit, the top and bottom horizontal portions of the C being positioned at the lower part of the stem and at the cross bar portion of the T strips and means for holding said laminations in position adjacent said strips.

13. In a means for producing a beam of compressional waves, an elongated radiating surface having magnetostrictive strip means formed as a part thereof running substantially the length of said surface, a plurality of C-shaped magnetic pole elements positioned at the sides of said strip, a coil surrounding said strip, the top and bottom portions of the C projecting over the coil and means for holding said pole elements in position against said strip at the lower end.

14. In a means for producing a beam of compressional waves, an elongated radiating element having magnetostrictive strip means extending substantially the length thereof and positioned symmetrical to the section of the radiator, coil means surrounding said magnetostrictive strip and providing electromagnetic flux for the same, and means for clamping said strip at the bottom in-

cluding means of magnetic material providing a magnetic flux path having a pole face adjacent the radiating element at the top of the strip.

15. Means for producing a beam of compressional waves comprising a group of parallelly arranged elongated radiators, strips of magnetostrictive material each supporting one of said radiators, means separating said radiators one from the other providing surfaces opposed to one another, said means also having a surface in the extension of the same plane as the radiators themselves and means supported between said radiators and said separating means for maintaining the surfaces of said separating means and said radiators that are opposed to one another free from contact with each other.

LAURENCE BATCHELDER.
